(57) **CLAIM**

The ornamental design for an outboard motor cowl, as shown and described.

DESCRIPTION

FIG. 1 is a rear perspective view of an outboard motor cowl according to our new and ornamental design;

FIG. 2 is a front perspective view thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top plan view thereof.

The portions of the outboard motor cowl shown in broken lines form no part of the claimed design.
